UNITED STATES PATENT OFFICE.

EDWARD E. OETTINGER, OF CHICAGO, ILLINOIS.

VALVE.

1,282,112.

Specification of Letters Patent. Patented Oct. 22, 1918.

Application filed March 27, 1915. Serial No. 17,443.

To all whom it may concern:

Be it known that I, EDWARD E. OETTINGER, a citizen of the United States, residing at Chicago, county of Cook, and State of Illinois, have invented certain new and useful Improvements in Valves, of which the following is a specification.

This invention relates to valves.

My invention particularly relates to valves for steam, hot water and hot air radiators, although it is not limited to such use, and it has for its objects the elimination of packing, the provision of a steam-tight closure, improved means for operating the valve, a novel valve construction, whereby the valve is rendered self-packing, the provision of novel means whereby the valve may be operated by foot pressure and thus do away with the necessity of repeatedly turning the valve wheel or handle commonly employed on steam and radiator valves; further, to provide a novel self-latching locking device for the operating means, and also to provide a cap, a valve-stem, and a spring arranged and adapted to coöperate in an improved manner, whereby the valve is self-opening and adapted to hold itself in an open position and may be closed, or partially so, by the pressure of the foot on the cap and against the action of the spring, the cap being locked by the self-latching device.

My improvements provide a packless, self-opening valve adapted for quick and easy opening or closing by foot manipulation and for the prevention of any leakage of steam.

I am aware that my invention is susceptible of many modifications, both in its valve structure, its operating means, latching means, and other features and parts. Some of those modifications are set forth fully hereinafter and are shown in the accompanying drawings; others will suggest themselves to those skilled in the art who may have my invention before them. I do not, therefore, limit myself to the details of construction shown in those forms which I have illustrated and described, unless so specified in the claims.

In the accompanying drawings:

Figure 1 is a vertical cross-section through the valve bend or shell and the operating mechanism, the valve being closed;

Fig. 2, a cross-section on line 2—2, Fig. 1;

Fig. 3, a horizontal section on line 3—3;

Fig. 4, a detail of the self-locking device;

Fig. 5, a detail section thereof;

Fig. 6, a perspective sectional view of the valve-turning device; 60
Fig. 7, a side elevation thereof; Fig. 8, detail views of the star wheel and a portion of the operating cap; Fig. 9, a fragmentary view of the upper portion of the valve; Fig. 10, a detail section showing the lower 65 pivotal connection of the valve; Fig. 11, a detail view showing the packing-grooves or channels in the rib at the bottom of the valve shell or casing; Fig. 12, a detail view showing the lower 70 pivotal connection of the valve when the latter is open; Fig. 13, a detail plan of the valve, dotted lines representing the depending portions at the lower pivotal part thereof; 75 Fig. 14, a detail of the spring; Fig. 15, a detail of a modified latch; Fig. 16, detail views of different forms of packless ribs and channels which may be used; 80 Fig. 17, a detail section of a modified valve operating mechanism; and Fig. 18, a view of another modification.

The valve shell or casing 1 is provided with internal screw-threads at its top as 85 shown at 2 for the connection of the fitting or shell 3 which carries the valve-operating devices. The fitting 3 has a concavity 4 extending to the bottom thereof and above this is a chamber 5. Rotatable in the concavity 4 and chamber 5 is the valve-turning device 6 which is shown in detail in Figs. 6 and 7. The lower portion thereof is of frusto-conical shape, as shown at 7 and fits snugly and rotatably in the concavity 4 and 95 is provided with a socket 8 to receive the squared upper end 9 of the butterfly valve 10, whereby said valve turns with the member 6. The member 6 has a flange 11 which bears upon the shoulder 12 of the fitting 3. 100 Projecting upwardly from the member 6 is a stem 13 which has two or more inclined or spiral ribs or feathers 14 which are of such a pitch that there will be imparted to the valve 10 a turning movement of ninety degrees under the influence of the operating devices to effect full closing or full opening of said valve and permitting positioning thereof at any intermediate point. Contained within the chamber 5 is a convolute 105 spring 15 (Fig. 14) whose base rests upon the upper face of the valve-turning device 6 110

and which surrounds the stem 13. I have adopted this form of spring because its coils are adapted to lie in the same plane when fully compressed, thus occupying small space, as shown in Fig. 17, for instance. Telescoping into the chamber 5 and over the fitting 3, is a push-cap 16 whose central portion is circular or, rather, of annular form and provided with a concavity or well 17 which receives the stem 13 and is provided with a spiral or inclined channel or groove 18 into which the rib 14 fits so as to be adapted to permit relative sliding of the cap 16 and the stem 13. If two of the ribs 14 be used, there will be employed two of the grooves 18. The spring 15 bears against the lower face of the cap 16 and by its expansion tends to hold the operating device 6 snugly rotatable in its concavity 4 so as to prevent escape of steam and also obviating the necessity of employing packing, thus eliminating a troublesome and expensive feature of valves. The form of the device 6 and cavity 4, in connection with the action of the spring 15, takes up all lost motion and wear. The spring retracts the cap upwardly, as shown in Fig. 1. The spring 15, by holding the valve turning device 6 snugly in concavity 4, insures a smooth, uniform wearing of the contacting surfaces of these parts and prevents the escape of steam. In any suitable manner I provide a rib and slot guiding connection between the cap 16 and the interior of the fitting 3. This is illustrated as consisting of grooves 19 in the outer face of the inner depending portion of the cap 16 and ribs 20 carried by the fitting 3 and projecting into the chamber 5. Such construction being employed, it is necessary to provide notches 21 in the member 6 so that the said member may be entered in the chamber 5 and fitted into its seat 4 before the cap 16 is placed in position. After the member 6 has thus been located, the groove 21 may be filled, below the lower ends of the ribs 20, with some material such as Babbitt metal 22 so that the member 6 is then prevented from coming out of position.

One or more pin-and-slot guiding connections 23 may be employed to prevent the cap 16 from becoming detached from the fitting 3.

Referring to Figs. 1, 4, 5 and 8, I there show locking or latching means for holding the cap in any position to which it may be depressed and correspondingly holding the valve 10 in any given position. The fitting 3 is provided with a rack 24 and the cap 16 carries a freely rotatable (except when checked) star wheel or pinion 25 which has trunnions 26 journaled in bearings 27 in the cap 16, pillow blocks or bearing members 28, held by suitable screws 29, serving to hold the trunnions 26 in position. So long as free to rotate, the star wheel 25 will

not lock the cap, but immediately a checking action is exerted on the star wheel, the cap will be locked. To that end I provide a latch 30 pivoted at 31 to a slight extension or lug on the side of the cap 16 so that the said latch may be swung to one side. The top 30^a of latch 30 lies below the upper surface of cap 16. The latch is provided with an arm 32 which is pivoted at 33 and is adapted to swing in an outward direction 75 only. The slight play that the arm 32 has, enables the star wheel to be caught in any position and consequently the cap can be held down to any point where it is depressed. The inclined arrangement of latch 30 (Fig. 80 4) enables the arm to be released by mere downward pressure on the top 30^a and when pressure is removed, the latch automatically restores itself to the locking position shown in Fig. 4.

As a modified form of latch, I provide the construction shown in Fig. 15, where a pawl 30^b is pivoted to the cap 16 and has a stop 30^c which will engage the extension of cap 16 to which the pawl is pivoted and prevent 90 the latch from moving so far over that it will not fall into the teeth 24 by gravity.

Normally the valve 10 is open. It may be partially or wholly closed by merely pressing the foot down upon cap 16 by 95 which action the star wheel 25 turns outwardly or in a counter-clockwise direction (Fig. 5), thus swinging arm 32 outwardly and allowing free outward and downward movement of the star wheel. As soon as the 100 pressure on cap 16 is removed, the expansion of spring 15 causes a reverse movement of the star wheel 25 and the forcing of arm 32 back against cap 16, thus locking the star wheel and hence the cap 16 and valve 10. 105 When the valve is closed, or partially closed, and it is desired to open it, merely touching the latch 30 with the foot will release the star wheel and thereupon the spring 15 will force the cap 16 upwardly and, through 110 the connection 14, 18, the member 6 will be turned and the valve 10 correspondingly turned open.

Referring now to Figs. 1, 3, 10, 11, 12 and 13, and particularly to Fig. 11, the interior 115 of the shell 1 is provided with a rib 34 which is continuous except at the upper part where the squared end 9 of the valve passes through. This rib is provided with concentric channels 35 which on one side of the 120 axis of the valve are in one face of the rib and on the other side of the axis of said valve they are on the other face of the rib, as will be clear from Figs. 3 and 11. Thus, in Fig. 11, the channels face the observer 125 and appear in full lines at the left of the gudgeon 36, while at the other side, or at the right, they are in dotted lines because they are in the opposite face of the rib. The rib is beveled away from the valve 10, as 130

shown at 37, such bevel being, in each instance, on the opposite side of the rib from the face which has the channels 35. The rib 34 at the bottom is cut away as at 38 to accommodate the hub 10^a of the valve 10. The gudgeon 36 projects upwardly from the upper surface of the cut-away portion 38 and is provided with a collar 36^a which fits in a concavity in the lower end of the hub 10^a. The top of the cut-away portion 38, and consequently the collar 36^a, is above the level 1^a of the interior of the shell 1 at the bottom thereof so that the pivotal connection of the valve is raised sufficiently high to avoid access of condensation water thereto and I thereby eliminate danger of rusting in the pivots. To accommodate drainage of condensation water, I provide at one point only, the transverse channel 39 which is exposed when the valve is open so that the water can drain therethrough, but when the valve is closed, a rib or flange 40 carried by the valve, enters the drain 39 and closes it, Figs. 3 and 13.

25 The channels 35 are cross connected by channels 41 disposed near the cut-out portion 38. The lowermost channels 35 are extended and communicated at 35^a with the cut-out portion 38.

30 The valve 10 is provided with ribs 42 which fit the channels 35, 41 and 35^a, such ribs being positioned and formed to correspond with and fit into these channels. At the upper end of the valve, Figs. 1 and 9, there are provided upright branch ribs 43 connected to the ribs 42, and the rib 34 has corresponding channels which bridge the channels 35 and receive the said ribs 43. Around the portion 9, the valve 10 is cut away as at 44 to receive the lower end of the member 6. This provides a sealed joint between the valve, its seat, and the turning device 6.

45 The ribs and channels obviate the necessity of using packing as they prevent the leakage of steam past the valve. If the steam leaks past one channel and rib received therein, it is arrested by the next channel and rib. At the lower part of the valve, as will be seen from Fig. 11, and the upper part of the valve, as will be clear from Figs. 1 and 9, the upright ribs and channels in conjunction with the opposite or cross ribs and channels, prevent access of the steam to the pivotal points of the valve.

50 I do not limit myself to any particular cross-sectional outline of the channels and ribs which fit into them, nor do I consider it essential that the channels be on the rib 34 because the shape of these channels and ribs may be varied and the ribs might be provided on the main rib 34 and the channels in the valve itself. Furthermore, the ribs may be formed integral or they may be attached parts connected either to the main

rib 34 or to the valve 10. The rib 34 may be a separate unit attached to casing 1, instead of integral therewith. In Fig. 16, I have shown some of the cross-sectional shapes these ribs and channels may assume, 70 but I am well aware that other forms could be resorted to.

75 On one side of the rib or flange 34 and on a given side of the pivot or gudgeon 36, the valve 10 is extended down below the level 75 of the cut-away portion 38, as will be seen from Figs. 10, 12 and 13 and also in Fig. 1; the end of the valve, that is, the vertical edge appearing, Figs. 1 and 10, at 45 on the side nearest the observer and the corresponding part or edge being shown by dotted lines 46 on the far side of the rib 34. When the valve 10 is fully open, the relative appearance of the parts is as shown in Fig. 12 and when closed, as in Fig. 10.

80 Referring to Fig. 17, I have shown a modified operating mechanism for a reciprocating or globe valve. The cap 16^a is directly connected to the stem 13^a which carries the valve, not shown. The parts are 85 shown in closed position with the spring 15 under full compression. It is desirable to employ a packing gland 47 for the stem 13^a held down by plate 47 screwed down on turning device 6. The latch of either Fig. 95 5 or Fig. 15 can be employed.

90 In Fig. 18, the valve operating mechanism is preferably employed with the stem 13^b of a reciprocating valve, the object being to not only move the stem longitudinally, but to 100 turn it so that the valve will be seated by a grinding or twisting action and will be correspondingly unseated. The cap 16 is prevented from turning on the fitting 3 by the pin-and-slot connection 23 and it has rib- 105 and-groove connections 19 with the fitting. 3. It is adapted to impart a turning movement to the stem 13^b by a spiral rib 14 engaging a slot in the cap 16, as in Fig. 1. Ball bearings 48 may be interposed between the head 49 of stem 13^b and the cap 16. When the cap 16 is depressed, it bodily shifts the stem 13^b with its head 49 and at the same time imparts a turning movement to said stem 13^b.

110 In the modifications of Figs. 17 and 18, the latching mechanism holds the valve fully opened, fully closed, or in any intermediate position.

115 Having thus described my invention, what I claim as new and desire to secure by Letters Patent, is:—

1. The combination with a valve, and a hollow fitting, of a concave seat in the hollow fitting, a tapered packing device received within the concave seat, valve-operating means comprising a reciprocatory push member arranged concentric to the valve and adapted to actuate the valve on both its advance and retraction movements, 130

5 a spring interposed between and bearing on the tapered packing device and the push member for the purpose of retracting the push member and for holding the packing device in the concavity, and a releasable latch adapted for securing the push member wherever positioned, to thereby hold the valve in any desired position.

2. The combination with a valve, and a 10 hollow fitting, of a concave seat in the hollow fitting, a tapered packing device received within the concave seat, valve-operating means comprising a reciprocatory push member arranged concentric to the valve and

15 adapted to actuate the valve on both its advance and retraction movements, a helical or convolute spring interposed between and bearing on the tapered packing device and the push member for the purpose of retracting the push member and for holding the packing device in the concavity, and a releasable latch adapted for securing the push member wherever positioned, to thereby hold the valve in any desired position.

25 3. The combination with a valve, and a hollow fitting, of a concave seat in the hollow fitting, a rotatory tapered valve turning device seated in the concave seat and adapted to turn therein, a reciprocatory 30 push member movable in relation to said valve turning device, an operative connection between the push member and the valve turning device, whereby the latter is turned by the former, a spring interposed between the valve turning device and the push member and serving the double function of retracting the push member and holding the valve turning device in the concavity, and means for holding the push member in different positions in opposition to the action 35 of the spring.

4. The combination with a valve, of operating means therefor comprising a rotary valve-turning device having a stem, a stationary fitting, a push member telescoping into said fitting and also telescoping with the stem of said valve-turning device, a spiral groove or slot and a member constituting an operative connection between the push-member 45 and said stem whereby the valve-turning device is turned by the reciprocations of the push-member, a helical or convolute spring contained within said fitting between the push-member and valve-turning device and surrounding said stem thereof, said spring being adapted to retract the push-member and to hold the valve-turning device seated, and means for holding the push-member in opposition to action of said spring.

60 5. The combination with a valve, of operating means therefor comprising a rotary valve-turning device having a stem, a stationary fitting, a push-member telescoping into said fitting and also telescoping with 65 the stem of said valve-turning device, a

spiral groove or slot and a member constituting an operative connection between the push-member and said stem whereby the valve-turning device is turned by the reciprocations of the push-member, a helical 70 or convolute spring contained within said fitting between the push-member and valve-turning device and surrounding said stem thereof, said spring being adapted to retract the push-member and to hold the valve-turning device seated, and a rack and 75 catch latching device for securing the push-member to the fitting at different points to hold the valve in any desired position.

6. The combination with a valve, and a 80 hollow fitting, of valve operating means comprising a push-member telescoped with the fitting, a concave seat in the hollow fitting, a tapered packing device received within the concave seat, a helical or convolute retracting spring located within the fitting and bearing against the push member and the tapered packing device, and means for securing the push-member against movement.

90 7. The combination with a valve, of operating means therefor comprising a spring-actuated push-member, and a releasable latch for said push-member embodying a rack and pinion or star wheel, and a releasable stop device engageable with said star wheel or pinion.

8. The combination with a valve, of operating means therefor comprising a spring-actuated push-member, and a releasable 100 latch for said push-member embodying a rack and pinion or star wheel, and a swinging latch having a pivoted piece engageable with the pinion or star wheel.

9. The combination with a valve, of a fitting, valve-operating means comprising a valve-turning device, a push-member telescoping with the fitting, guiding means adapted to prevent turning of said push-member, a spiral or convolute spring within 110 the fitting and interposed between the valve-turning member and the push-member, a spiral slot and a member received therein constituting an operative connection between the push-member and valve-turning 115 device, a rack on the fitting, a pinion or star wheel carried by the push-member and engaged with said rack, and a swinging latch carried by the push-member and having a pivoted piece which is engageable with the 120 pinion or star wheel to lock the latter and hence the push-member in any desired position.

10. The combination with a valve casing or shell having a continuous circular internal flange or rib, of a butterfly valve adapted to seat against said continuous flange or rib when closed, and valve-operating means comprising a concave seat within the valve casing, a rotatory tapered valve turning 125 130

member fitting in said seat, a push member, and an operative connection between said push - member and valve turning member whereby the sliding movement of the push-member swings said valve, and a spring bearing on the push member and valve turning member.

11. The combination with a valve casing or shell having a continuous circular inter-
10 nal flange or rib, of a butterfly valve adapt-
ed to seat against said continuous circular flange or rib when closed, said valve and flange being provided with channels and ribs arranged to fit within each other when
15 the valve is closed and extending from the region of one end of the axis of the valve to the other end thereof with lateral branch ribs and channels connecting the main ribs and channels aforesaid in the region of the
20 ends of the axis of the valve, to thereby provide a sealed joint between the valve and its seats, and means for operating the valve.

12. The combination with a valve casing or shell having an internal flange or rib, of
25 a butterfly valve adapted to seat against said flange or rib when closed, said butterfly valve resting on, and having a pivotal connection with, the said internal rib or flange at a point higher than the internal surface of
30 the valve casing or shell adjacent thereto, and terminating short of said internal surface of the casing, whereby the said pivot is protected from rusting, and means for operating the valve.

35 13. The combination with a valve casing or shell having an internal flange or rib, of a butterfly valve adapted to seat against said flange or rib when closed, said butterfly valve resting on, and having a piv-
40 otal connection with the said internal rib or flange at a point higher than the internal surface of the valve casing or shell adjacent thereto, said internal rib or flange being provided with a condensation water drain or
45 vent below the point of support of the valve and said valve having a rib adapted to close said drain or vent when the valve is closed, whereby the pivot is protected from rusting, and means for operating the valve.

50 14. The combination with a valve casing or shell having an internal flange or rib, of a valve-turning device having a tapered part fitting a concavity in the shell or casing and protruding into the valve chamber, and a
55 butterfly valve provided with a projection received within and engaging the tapered part of the valve-turning device, said valve being cut away or notched on opposite sides of said projection and snugly receiving the
60 tapered end of the valve-turning device, and mating ribs and channels provided on the

valve and its seat-flange in the region where the tapered end of the valve-turning device engages the notched portion of the valve.

15. The combination with a valve casing 65 or shell having an internal flange or rib, of a butterfly valve adapted to seat against said flange or rib when closed, said flange having a cut out portion whose upper sur-
70 face is at a point higher than the internal 75 surface of the valve casing or shell adjacent thereto, a pivot gudgeon provided with a collar, rising from said cut-out portion, a drain or vent opening extending through the flange in one corner of the cut-out por-
75 tion, a butterfly valve resting upon said cut-out portion and mounted on said pivot gudgeon, said valve being provided with a rib adapted to enter the drain or vent when the valve is closed, said valve extending 80 downwardly below the upper level of the cut-out portion on opposite sides of the flange aforesaid.

16. In a valve, the combination with a fitting or shell having a tapered concavity, 85 of a valve-turning device having a conical part fitting and adapted to turn in said concavity, a valve operable by said valve-turn-
ing device, and a spring acting on said valve-turning device adapted to hold it in 90 said concavity.

17. In a valve, the combination with a fitting or shell having a tapered concavity, 95 of a valve-turning device having a conical part fitting and adapted to turn in said con-
cavity, a valve operable by said valve-turn-
ing device, means for turning said valve-
turning device which is movable in relation thereto, and a spring interposed between 100 said valve-turning device and said turning means and which retracts the means for turning the valve and also holds the valve-
turning device in said concavity.

18. The combination with a valve casing or shell having a continuous circular internal 105 flange or rib, of relatively offset semi-circu-
lar disks constituting a single butterfly valve of circular shape adapted to seat against said flange or rib when closed, said valve and flange being provided with double lines of 110 channels and cross channels connecting them and corresponding ribs arranged to fit within each other when the valve is closed to thereby provide a sealed joint between the valve and its seat, and means for operating 115 the valve.

In testimony whereof, I hereunto affix my signature in presence of two witnesses.

EDWARD E. OETTINGER.
